UNITED STATES PATENT OFFICE.

GUSTAV SCHOENFELD, OF GREAT FALLS, MONTANA.

LEAF TURNER.

Application filed November 5, 1927. Serial No. 231,240.

This invention is a device for turning the leaves of music whereby a performer will not be interrupted by the necessity of turning leaves successively by hand. The object of the invention is to provide a mechanism which will operate with certainty to successively turn the leaves as a composition is played and relieve the performer of the necessity of interrupting the performance in order to turn the leaves. The invention provides simple and compact mechanism whereby a light tap of the performer's foot will successively turn the leaves from right to left and will hold them positively in position to permit reading of the music. The invention also provides means whereby a book containing a composition which is to be performed may be firmly supported in an upright position.

20 The invention is illustrated in the accompanying drawings and will be hereinafter fully set forth. In the drawings:

Fig. 1 is a front elevation of a leaf turner constructed in accordance with my invention.

25 Fig. 2 is a plan view of the operating mechanism.

Fig. 3 is a sectional elevation showing the working elements.

30 Fig. 4 is an enlarged transverse section showing the arrangement of the latches whereby the leaf-turning arms are held in their initial positions.

35 Fig. 5 is an enlarged detail section showing the manner of mounting the turning arms.

Figs. 6 and 7 are, respectively, a front and rear elevation of the feeding plate whereby the turning arms are successively released.

In carrying out my invention, there is provided a base member comprising a bottom plate 1 and a back plate 2, whereby a substantially box-like base is produced adapted to rest upon the desk of a piano or upon the ledge of a music stand. To protect the working parts of the device from injury by chance blows, a casing 3 is provided to extend over the top of the base member and across the same in front of the working parts, the position of the front edge of this casing being indicated by the dotted line 4 in Fig. 2. In the top of the casing 3 and in the back wall 2 of the box, openings or recesses, indicated at 5, are provided to receive pins 6 which rise from the base member to a sufficient

50 height to accommodate a bound book and

support the same in upright position. It will be understood upon reference to Fig. 4, that the pins or rods 6 are arranged two adjacent the front of the device and two adjacent the back of the same, and that the 60 sides of the book are placed between these upright pins or rods in opened position, the leaves or pages containing the composition which is to be performed being disposed in front of the front pins or rods. To aid in 65 holding the book in its open position and prevent collapse of the same, a retaining device consisting of a plate 7 and a spring finger 8 secured upon the front side thereof, is fitted in a recess provided therefor in the 70 back plate 2 at the center of the same, the back of the book being received between the plate and the finger in an obvious manner. A similar plate 9 having a spring finger 10 is carried by a rod 11 slidably fitted upon the 75 rear rods 6 to engage the upper end of the back of the book so that the book will be firmly supported in such a position that the notes may be easily read.

Adjacent the front of the base plate, and at 80 the center of the same, a circular post 12 is secured, and loosely fitted around the post are superposed hubs or collars 13 to each of which is attached a leaf-turning arm 14, the arm extending radially from the hub member 85 and being constructed of resilient metal and terminating in a spring coil 15 having at least two turns whereby it may be engaged with the lower edge of a sheet of music to cause the sheet or leaf to follow the movement of the arm. Within each hub or collar is a volute spring 16 having one end attached to the post 12 and its opposite end attached to the hub or collar, the arrangement being such that when the leaf-turning 90 arm is disposed at the right hand side of the device, as shown in Figs. 1 and 2, the spring will be placed under tension and upon the arm being released it will be at once swung to the left hand side of the device under 95 the influence of the spring. To retain the several leaf-turning arms at the right hand side of the device so that the several sheets or leaves of the music will be in their initial positions, I provide a plurality of latches 17, 100 each of which is adapted to engage one of the turning arms. These latches are disposed in a vertical series at one side of the post 12 and the hubs mounted thereon and are pivotally mounted, as at 18, within a 105 110

bracket or housing 19 which is secured upon the base plate 1. The front ends of the several latches are beveled upwardly and rearwardly, as shown at 20, whereby a turning 5 arm, engaging the end of the latch, will be guided upwardly to rest on the arm and may drop into a notch 21 formed in the upper side of the latch adjacent the front end of the same. The rear ends of the latches 10 pass through slots in a trip plate 22 which is slidably supported upon the base of the device and upon the back of this trip plate are a plurality of light spring fingers or rods 23, each of which projects over and 15 bears upon the rear end of one of the latches, as will be understood upon reference to Fig. 4. The rear ends of the latches will thus be held normally depressed so that the front ends thereof will engage the leaf-turning 20 arms and hold the same against movement. The several slots 24 in the trip plate 22 are disposed one vertically over another so that they will respectively receive the rear ends of the latches and each slot has an offset 25 portion 25 which is adapted to be brought against the rear end of the respective latch in the operation of the device, so as to rock the latch and release the turning arm engaged thereby. By referring to Figures 6 30 and 7, it will be noted that the offsets of the several slots are arranged at different distances from the ends thereof and follow approximately an obliquely disposed line extending from the left hand end of the lowest slot to the right hand end of the uppermost slot, the result being that the offsets will engage the respective latches successively so that they will be released one at a time and the proper turning of the leaves thereby assured. The trip plate 22 is supported 35 on edge by a guide bracket 26 rising from the bottom of the base member of the device and also by a finger 27 projecting rearwardly from the bracket 19 and playing in a horizontal slot 28 formed in the trip plate adjacent the lower edge of the same.

To actuate the trip plate there is provided a resilient dog or pull rod 29 having a laterally disposed terminal 30 adapted to successively engage the ratchet teeth or notches 31 formed in the upper edge of the trip plate. This resilient pull rod is secured to a cross head 32 slidably mounted within the compartment forming the base of the device and 40 from the said head a guide arm 33 extends in the opposite direction from the pull rod to pass through a bracket 34 so as to hold the head to a rectilinear path. The guide rod 33 passes entirely through the guide bracket 34 and at the left hand side of the same carries an abutment plate 35 which is spaced from the guide bracket, a spring plate 36 being fitted around and engaged with the abutment plate and the adjacent wall of the bracket 34 so as to hold the abutment plate

normally toward the bracket. Disposed between the abutment plate and bracket is a flexible bulb 37 which is shown in the drawings as collapsed, but which, when inflated, will obviously cause the abutment plate 35 70 to move away from the guide bracket 34 against the tension of the returning spring 36. Upon collapse of the bulb 37, the cross head 32 and the pull rod 29 will return to their initial positions under the influence of 75 said spring. It will thus be seen that a reciprocatory movement is imparted to the pull rod so that it will alternately engage one of the ratchet teeth on the upper edge of the trip plate and pull the said plate to the left and then return, riding over the plate to engage a succeeding tooth. The trip plate will thus be actuated step by step so as to successively trip the latches and release the leaf-turning arms. To inflate the bulb 37, 80 I have illustrated a suction bulb 38 which may be disposed adjacent the pedals of a piano or at the foot of a music stand so that it may be easily reached by the foot of the performer and this bulb is connected 85 with the inflation bulb 37 by means of a flexible pipe 39 arranged in any convenient or preferred manner. When the bulb 38 is deflated by pressure of the performer's foot, the bulb 37 will be inflated and the pull rod 29 actuated to turn a leaf in a manner which will be well understood from the foregoing description.

To set the device, I provide a pusher frame 40 which is slidably mounted in a bracket 41, 100 erected upon the base 1, and which has a lateral terminal or finger 42 disposed below the pull rod 29 and adapted to impinge against the adjacent edge of the trip plate, a retractile spring 43 being disposed between and attached to the bracket 41 and an adjacent portion of the frame so as to hold the frame normally retracted from the trip plate. A rock shaft 44 is journaled in a suitable bearing upon the base of the device and is provided at 105 its inner end with a crank 45 disposed between the cross head 32 and the end of the frame 40 and adapted to bear against the frame, as clearly shown in Fig. 3. The outer end of this rock shaft 44 is equipped with a lever or 110 handle member 46. To set the device in initial position, the lever or handle 46, is swung upwardly and over toward the right so that the crank 45 will be correspondingly moved and this movement of the crank will force 115 the frame toward the right so that its terminal 42 will impinge against the adjacent end edge of the trip plate and slide the same to the right, it being noted that the pull rod 29 has a depressed offset portion 47 which extends into the path of the terminal 42 of the pusher frame so that just before the frame engages the trip plate it will lift the pull rod out of engagement with 120 the plate and the plate will thus be free to 125

130

slide to its initial position. When the plate has been thus moved to its proper initial position, the lever 46 is released and the parts will then return to the position shown in Fig. 3

5 under the influence of the spring 43. It will be noted at this point that the crank 45 bears against the cross head 32 and it is, therefore possible to operate the device to turn the leaves by rocking the shaft 44 in a direction 10 to move the crank 45 toward the bracket 34, consequently imparting to the cross head the same movement that was imparted thereto by the inflation of the bulb 37 previously described. It may sometimes be preferred to so proportion the parts that the crank or lever handle 46 will be disposed outside of the base member of the apparatus and have attached thereto a finger piece to facilitate its engagement by the left hand of the performer, 15 or a foot pedal may be connected with the member 46 in a well understood manner. After the trip plate has been set in its initial position, illustrated in full lines in Fig. 3, the leaf-turning arms are swung around to the right, thereby putting the springs 16 under tension and causing the several arms to ride onto and be engaged by the several latches, as indicated in Fig. 4. When the trip plate receives its first movement under the influence 20 of the pull rod 29, it will be moved a distance equal to the distance between any two successive ratchet teeth 31 and this movement will cause the offset 25 in the lowest slot 24 to ride against the rear end of the lowest 25 latch 17, thereby rocking the rear end of the latch upwardly and causing the front end thereof to release the lowest turning arm, which will thereupon at once swing over to the left. In like manner, the several leaf- 30 turning arms will be successively released in an ascending series.

It is to be understood that the accompanying drawings are illustrative only and I do not restrict myself to the exact details shown 45 therein. For instance, instead of the bulb 37, I may employ a cylinder in which the abutment plate 35 will act as a piston to receive the pressure directed through the pipe 39.

From the foregoing description, taken in 50 connection with the accompanying drawings, it will be seen that I have provided an exceedingly simple, compact, easily operated, and efficient device whereby the leaves of a piece of music may be successively turned as the composition is played without requiring the player to interrupt his performance for turning the leaves.

Having thus described the invention, what I claim is:

60 1. A leaf turning mechanism comprising a plurality of leaf-turning arms, means for swinging the arms from right to left, a plurality of latches arranged to each engage one of the arms and hold it in initial position, a horizontally 65 slidable trip plate provided

with a series of horizontal slots arranged vertically one above another and each receiving the rear end of one of the latches, the slots being provided with offset portions in stepped relation to successively engage the respective 70 latches whereby to release them from the turning arms, and means for imparting a step by step movement to the trip plate.

2. A leaf turning mechanism comprising a plurality of leaf-turning arms, a plurality of 75 latches each engaging one of the arms and retaining it in initial position, a horizontally slidable trip plate engaging the latches and arranged to release them successively from the respective arms, a pull rod arranged to alternately engage and ride on the trip plate, and means for actuating said pull rod whereby to impart step by step movement to the trip plate.

3. A leaf turning mechanism comprising a 80 plurality of leaf-turning arms, means for swinging the arms from right to left, a plurality of latches arranged each to engage one of the arms, a horizontally slidable trip plate 85 engaging the rear ends of the latches and constructed to successively release them from the respective turning arms, a plurality of ratchet teeth on a horizontal edge of the trip plate, a resilient pull rod adapted to successively engage said ratchet teeth, and means for reciprocating said pull rod whereby to impart 90 a step by step movement to the trip plate.

4. A leaf turning mechanism comprising a 95 plurality of leaf-turning arms, means for swinging the arms from right to left, a plurality of latches arranged each to engage one of the arms, a trip plate engaging the rear ends of the latches and constructed to successively release them from the respective turning arms, a plurality of ratchet teeth on 100 an edge of the trip plate, a resilient pull rod adapted to successively engage said ratchet teeth, means for reciprocating said pull rod whereby to impart a step by step movement to the trip plate, and means for simultaneously 105 releasing the pull rod from the trip plate and returning the trip plate to initial position.

5. A leaf turning mechanism comprising a 110 plurality of turning arms, a plurality of latches each engaging one of the arms and retaining it in initial position, a horizontally slidable trip plate engaging the latches and constructed to successively release them from the respective turning arms, a pusher arranged to engage the trip plate and set the 115 same in initial position, means for actuating the pusher, means for withdrawing the pusher from the trip plate, a resilient pull rod engaging the trip plate and having an offset portion extending into the path of the pusher whereby the pull rod will be released from the trip plate when the pusher is actuated, and means for reciprocating the pull rod whereby to impart step by step releasing 120 movement to the trip plate.

6. A leaf turning mechanism comprising a plurality of leaf-turning arms, a plurality of latches arranged to engage the respective arms, a trip plate engaging the latches and 5 constructed to successively release them from the respective turning arms, a pull rod arranged to engage the trip plate, a cross head carrying said pull rod, a guide arm extending from the cross head, a bracket supporting and 10 guiding said arm, an abutment on the guide arm in spaced relation to the bracket, an inflatable bulb disposed between and bearing against the guide bracket and the said abutment, yieldable means for holding the abutment toward the bracket, and means for inflating the bulb and thereby moving the abutment in opposition to said yieldable means whereby to reciprocate the pull rod and impart step by step movement to the trip plate. 15
7. A leaf-turning mechanism comprising a plurality of turning arms, means for swinging the arms from right to left, a plurality of latches each holding one of the arms in initial position, a slidably mounted trip plate 20 engaging all the latches and constructed to successively release them from the respective arms when moved in one direction, a pusher arranged to engage the trip plate and set the same in initial position, yieldable means for holding the pusher out of engagement with the trip plate, a rock shaft disposed in angular relation to the pusher, a crank at the inner end of the rock shaft bearing against the end of the pusher to actuate the pusher for setting the trip plate, a pull rod arranged to alternately engage and ride over the trip plate, and means for actuating the pull rod to impart step by step movement to the trip plate, the pull rod having an offset in the path of the pusher whereby when the pusher is actuated to set the trip plate the pull rod will be released from the trip plate. 25
- 30

engage and ride over the trip plate, and means for actuating the pull rod to impart step by step movement to the trip plate, the pull rod having an offset in the path of the pusher whereby when the pusher is actuated to set the trip plate the pull rod will be released from the trip plate. 35

8. A leaf-turning mechanism comprising a 40 plurality of turning arms, means for swinging the arms from right to left, a plurality of latches each holding one of the arms in initial position, a slidably mounted trip plate 45 engaging all the latches and constructed to successively release them from the respective arms when moved in one direction, a pusher arranged to engage the trip plate and set the same in initial position, yieldable means for holding the pusher out of engagement with the trip plate, a rock shaft disposed in angular relation to the pusher, a crank at the inner end of the rock shaft bearing against the end of the pusher to actuate the pusher for setting the trip plate, a pull rod arranged to alternately engage and ride over the trip plate, and means for actuating the pull rod to impart step by step movement to the trip plate, the pull rod having an offset in the path of the pusher whereby when the pusher is 50 actuated to set the trip plate the pull rod will be released from the trip plate. 55

In testimony whereof I affix my signature.
GUSTAV SCHOENFELD. [L.S.]
